UNITED STATES PATENT OFFICE

161,210

RIGID COVERING FOR AWNINGS OR LIKE STRUCTURES

Donald H. Ruggles, Tulsa, Okla.

Application September 19, 1949, Serial No. 5,080

Term of patent 14 years

(Cl. D21—6)

To all whom it may concern:

Be it known that I, Donald H. Ruggles, a citizen of the United States, residing at Tulsa, in the county of Tulsa and State of Oklahoma, have invented a new, original, and ornamental Design for a Rigid Covering for Awnings or Like Structures, of which the following is a specification, reference being had to the accompanying drawing, forming a part thereof.

Figure 1 is a perspective view of one face of a rigid covering for awnings or like structures showing my new design.

Figure 2 is a perspective view showing the opposite face of the same.

Figure 3 is a plan view of the face shown in Figure 1.

Figure 4 is a longitudinal section taken on the line 4—4 of Figure 3.

Figure 5 is a transverse section on the line 5—5 of Figure 3.

I claim:

The ornamental design for a rigid covering for awnings or like structures, as shown.

DONALD H. RUGGLES.
